UNITED STATES PATENT OFFICE.

EDMUND W. BINGLE, OF CHICAGO, ILLINOIS, ASSIGNOR TO HERZ BED COMPANY, OF CHICAGO, ILLINOIS, A CORPORATION OF ILLINOIS.

SPRING-MATTRESS STRUCTURE.

Application filed November 12, 1927. Serial No. 232,729.

My invention relates to spring mattress structure for beds, and one of the objects is to provide a structure of this character wherein the spring action is evenly and uniformly distributed throughout the entire mattress surface thereby providing maximum ease and comfort for the user.

Another object is to provide a highly efficient spring mattress structure which is simple in construction and cheap to manufacture.

A further object is to provide a mattress structure including a plurality of springs which are so positioned and associated with each other as to carry out the foregoing objects, at the same time being adapted to carry maximum loads, whether evenly or unevenly distributed, without permanent distortion.

Other objects and advantages will become apparent as this description progresses and by reference to the drawings wherein,—

Figure 1 is a top plan view of a portion of a spring mattress structure embodying my invention. Since both ends and sides of the mattress structure and the spring members associated therewith are identical, only a portion of the entire mattress structure is shown.

Fig. 2 is a horizontal section of the structure of Fig. 1 taken immediately above the lower set or tier of springs as indicated clearly on line 2—2 of Fig. 4;

Fig. 3 is a side elevation of the portion of the mattress adjacent the rounded corner shown in Fig. 1, the exterior part of such structure only being shown for clearness;

Fig. 4 is a vertical section taken on line 4—4 of Fig. 1;

Fig. 5 is an enlarged horizontal section taken at a point indicated by line 5—5 of Fig. 4;

Fig. 6 is a vertical section taken at line 6—6 on Figure 5 and clearly showing the manner of interengaging the springs of the upper and lower tiers;

Fig. 7 is an enlarged vertical section taken on line 7—7 of Fig. 4.

Referring particularly to the form shown in the drawings, I may employ a rectangular-shaped frame consisting of side bars 10 and end bars 11 formed, preferably, of angle iron and rigidly fastened together by a plurality of bolts or rivets as indicated at 12. The side and end bars at both sides and

ends of the bed are identical, as well as the structure associated therewith, and for that reason only a portion of the structure is shown in the drawings. A plurality of intermediate lateral bars 13, preferably 60 equally spaced, are carried by the side bars 10 throughout their length, these lateral bars 13 being formed from flat metal strips to provide a central U-shaped depending portion 14 with its base part turned upwardly at 65 right angles to present an edged supporting surface. The U-arms of these strips are extended horizontally and bolted or riveted to the horizontal flange of the side bars as indicated at 15.

The spring structure which I employ is supported by the frame and, preferably, takes, in part, the form of a plurality of funnel-shaped springs 16 having a lower cylindrical base portion 16^a seated upon the horizontally-extending arms of the intermediate bars 13 with their lower coils interengaged therewith. These coils are further anchored to the bars 13 by a wire 17 laced upon the bars 13 and through the lower coils 80 in an obvious manner (Fig. 3), the ends of such wires being hooked as at 18 to prevent disengagement from the springs 16 at the ends. The end bars 11 support a plurality of equally spaced coil springs 19 which have an upper funnel-shaped part 19^a and a lower barrel-shaped part 19^b. The lower part of these springs is engaged with and anchored to the end bars by passing the lowermost coils through suitable openings in the vertical flange of that bar in a manner well known. The springs 16 and 19 serve as border springs and, due to their shape, provide, in effect, a double spring action in conjunction with other and inner springs to be 90 described later. The upper coils of these border springs are held in aligned position and securely interlocked with and by a border rod 20 by a wire 21, in a well known manner as shown in Fig. 3.

Intermediate the border springs, I employ two tiers (upper and lower) of springs arranged in rows, the springs 22 of the lower tier being arranged in staggered relation to the springs 23 of the upper tier. All of 105 these springs, including the border springs, are equally spaced and arranged so as to lie in uniformly spaced lateral and longitudinal rows extending throughout the length and width of the mattress structure. 110

The springs 22 of the lower tier or rows are funnel-shaped and the lower part of each coil is supported upon the adjacent upturned edge of the intermediate bars 13 and are 5 anchored thereto by wires 24 extending longitudinally of the frame and looped through the lower coils of such springs and under their supporting bars 13 (Figs. 4 and 7).

The springs 23 of the upper tier or row 10 are also funnel-shaped. The lower springs are so spaced that the adjacent edges of their upper coils lie closely together and the lowermost coils of upper springs are interengaged or turned upon the adjacent upper 15 coils of the lower springs, so that a portion of each adjacent upper coil lies within the coils of the upper springs 23 (Figs. 5 and 6). The lower springs thus support the upper springs and loads imposed upon the 20 upper springs will be partially borne by the lower springs and, due to the staggered relation of these springs, the spring action is equally distributed along the upper surface.

It is desirable that the upper and lower 25 springs be positively secured together (Figs. 5 and 6) and held in predetermined lateral and longitudinal alignment, and to this end I employ longitudinal wires 25 which are anchored to the end-border coils 19 and pass 30 through the lower coils of the upper springs 23 and, preferably, beneath the portions of the adjoining upper coils of the lower springs 22 which are within the lower coils of such upper springs. Similar wires 25^a 35 are also carried by the side border springs 16 at the base of their funnel-shaped portion, such wires being anchored to the end springs of this group. The wires 25 and 25^a are provided with depending humps throughout 40 their length, as shown by wire 25^a in Fig. 3, to add strength, lessen the possibility of displacement of the springs along the wires, and to aid generally in positively anchoring the coils together. It will be noted that cer- 45 tain of these humps are so located and shaped (Figs. 3 and 6) that they extend downwardly within the coils of the upper springs which further aids in holding the upper springs in place (Fig. 6). To com- 50 pletely and positively secure the springs 22 and 23 and 16 and 19 together as a spring unit, lateral wires 26 are anchored to oppo- 55 site side-border coils 16 at the base of their funnel-shaped portion and preferably, at 60 right angles to the longitudinal wires 25 and 25^a. These wires 26 extend along the upper portion of the lower coils and pass through and within the lower coils of the upper springs in such a way as to loop over the 65 enclosed section of the upper coils of the lower springs, as shown in Fig. 6, thereby positively securing the coils together and preventing lateral or longitudinal displace- 70 ment of the same. The lower springs 22 ad- 75 jacent the side-border coils are of lesser

width at the top than the other coils of that group and their upper portions adjacent the springs 16 are supported and confined by the respective lateral wire 26 which passes thereover. These latter springs are thusly anchored to the side border coils so as to pro- 70 vide a staggered relation between such springs and so that loads imposed upon the border springs 16 will be partially imposed upon and borne by the adjacent lower 75 springs 22. Wires 26^a similar to wires 25^a serve to additionally secure the end border springs 19 (Fig. 1).

The upper springs 23 are further sup- 80 ported and held in spaced relation at the top by a plurality of cylindrical coil springs 27 and 28. These springs 27 and 28 are ar- 85 ranged at right angles to each other with their central coils turned or wound upon each other (Fig. 1) so that loads imposed upon one of such springs are partially borne by the other. Each spring 27 or 28 is pro- 90 vided with a hook at opposite ends which is connected to the uppermost coils of the dia- 95 ginally opposing springs 23 so that all of the upper springs 23 are connected together in a uniformly yieldable manner; and such upper springs are also connected to the side and end border springs 16 and 19 by the springs 27 and 28 (Fig. 1).

It is believed that the spring action is clear from the foregoing. Loads imposed upon the mattress surface will be borne in part by both the upper and lower springs 23 and 22 and by the border-springs 16 and 19. The staggered relation between the upper and lower springs and between the side- 100 border springs and lower springs with the spring connections between the upper springs and border springs presents a con- 105 tinuous spring surface throughout the mat- 110 tress structure and the spring action is uni- 115 form and equally distributed throughout the mattress surface, all of which provides for maximum comfort for the user. Furthermore, according to my invention the spring devices are so anchored and secured together that the above action is insured and they are held in a predetermined alignment and the possibility of sagging and permanent dis- 120 tortion is eliminated without interfering with the desired spring action and uniform distribution of the same.

I have shown and described only one em- 125 bodiment of my invention, but it is to be understood that various changes and modifi- 130 cations may be made therein without de- 135 parting from the spirit and scope of my in- 140 vention, as defined by the claims which follow.

I claim:

1. In a spring mattress, a frame, lower coil springs carried by the frame, and upper coil springs mounted directly upon and in engagement with the lower coil springs in 130

staggered relation thereto, said upper and lower springs being interlocked directly with each other to provide a plurality of coacting coil groups, and means for connecting the groups together for coaction.

2. In a spring mattress, a frame, coil springs mounted upon said frame with their upper coils lying close together, other coil springs carried upon the first-named coil springs, the lower coils of the latter springs being intercoiled with the upper coils of the first-named supporting springs, said first and second named coil springs having their vertical axes relatively offset, and means engaging said intercoiled portions for securely fastening said springs together.

3. In a spring mattress, a frame, outer coil springs mounted on said frame, inner coil springs mounted on said frame, and other coil springs mounted on said inner coil springs in staggered relation thereto, said inner and other coil springs being directly interlocked with each other.

4. In a spring mattress, a frame, side border springs carried by said frame, end border springs carried by said frame, inner springs carried by said frame between said side and end border springs, upper springs carried upon said inner springs, in staggered relation thereto with their lower coils intercoiled with the upper coils of said inner springs so that a portion of said upper coils lie within the lower coils of said upper springs, longitudinal wires anchored to said end springs and passing through the lower coils of said upper springs, and lateral wires anchored to said side-border coils and passing through the lower coils of said upper springs and over said enclosed upper coils and said longitudinal wire.

5. In a spring mattress, a frame, side border coil springs mounted upon said frame, end border coil springs mounted upon said frame, inner coil springs mounted upon said frame, upper coil springs each having their lower coils intercoiled with the upper coils of the adjacent supporting inner coil springs so that a portion of said upper coils lie within said lower coils, spring members connecting the upper coils of the upper springs to each other and to said side and end border springs, longitudinal wire members anchored to said end springs and passing through the lower coils of said upper springs, said members having depending humps lying within the coils of said upper springs to pre-

vent longitudinal displacement of said upper coils, lateral wire members anchored to said side border springs and extending through the lower coils of said upper springs and above the upper coils of said inner springs, said lateral members having upwardly directed humps lying within the lower coils of said upper springs to prevent lateral displacement of said upper springs, the opposed humps on said wire members serving as a closed pocket for the portions of the upper coils of the inner springs to securely anchor said inner and upper springs together.

6. In a spring mattress, a plurality of coil springs including single side border springs, inner springs, upper springs supported directly upon and intercoiled with the upper coils of said inner springs and intercoiled therewith, the vertical axes of said inner and upper springs being relatively offset, and wire members anchored to said side springs and interengaged with the intercoiled portions of said inner and upper springs, said members serving to confine and support the upper coils of said inner springs which are mounted adjacent said side springs.

7. In a spring mattress, a plurality of coil springs, some of which are mounted upon each other in staggered relation with the lower coils of the upper springs intercoiled with the upper coils of the two adjacent lower springs, and fastening devices disposed in criss-cross relation and interlaced with the intercoiled portions of said upper and lower springs for securing and holding said springs in aligned relation.

8. In a spring mattress, a plurality of coil springs, some of which are mounted upon each other in staggered relation with the lower coils of the upper springs intercoiled with the upper coils of the two adjacent lower springs, and means for positively interlocking said upper and lower springs, said means comprising lateral and longitudinal wires passing through and oppositely humped within the lower coils of said upper springs so as to prevent lateral and longitudinal displacement of said upper springs and to confine and prevent disengagement of the upper coils of said lower springs.

In testimony whereof, I have subscribed my name.

EDMUND W. BINGLE.
